DESIGN FOR A STUFFED TOY ANIMAL UNIT

Benjamin F. Michtom, New Rochelle, N. Y., assignor to Ideal Novelty & Toy Co., Long Island City, N. Y., a corporation of New York

Application January 22, 1943, Serial No. 109,326

Term of patent 3½ years

To all whom it may concern:

Be it known that I, Benjamin F. Michtom, a citizen of the United States, residing at New Rochelle, in the county of Westchester and State of New York, have invented a new, original, and ornamental Design for a Stuffed Toy Animal Unit, of which the following is a specification, reference being had to the accompanying drawing, forming part thereof.

In the drawing

Fig. 1 is a front elevational view of a stuffed toy animal unit showing my new design; the smaller figure being permanently secured to the larger figure.

Fig. 2 is a side elevational view thereof.

I claim:

The ornamental design for a stuffed toy animal unit, as shown.

BENJAMIN F. MICTOM.
